FOUNTAIN TOOTHBRUSH

Filed Dec. 4, 1946

Inventor:
Charles H. Finton
By: John R. & Potts
his Attorney.

UNITED STATES PATENT OFFICE

2,516,195

FOUNTAIN TOOTHBRUSH

Charles H. Finton, Chicago, Ill.

Application December 4, 1946, Serial No. 714,100

5 Claims. (Cl. 15—128)

1

This invention relates to improvements in fountain toothbrushes. More particularly, this invention relates to improvements in toothbrushes and toothbrush attachments. It relates to toothbrushes of the kind that are used in combination with liquid supply, and commonly known as fountain brushes.

The invention presents a simple yet positive means of detachably securing a fountain element to a toothbrush. It avoids disturbing the liquid connection in interchanging brushes.

The toothbrush of my invention has means whereby the liquid is conveyed through a tube from the member having a tube which extends through the handle into the brush head.

At its end in the brush head, the tube has apertures for the supply of liquid to the brush. Also, the construction of my invention has improved means for easily and efficiently connecting the said tube to the brush handle.

Naturally, everyone has his own toothbrush, and no one wants to use the brush of another. The means of my invention provide for easily taking off the brush of one person and quickly substituting the brush of another person, and still maintaining leak-proof communication with the source of supply. My arrangement for connecting the brush handle to a source of supply, or from the member, involves a unique construction for enabling quick changes to be made from one brush to another, while maintaining the same leak-proof condition. In short, the liquid supply tube is encircled by a cylindrical portion.

This cylindrical portion has a spiral spring in the preferred form. The cylindrical portion also has a key, and there is a groove in the end of the brush handle. This groove is brought in registry with the key, and the handle is pushed in the cylindrical portion against the spring, until the key comes to the end of the slot of the groove, when the handle is turned in an angular direction.

This results in the brush handle being securely held in the cylindrical portion, with the spring pressing against the end of the brush.

Other objects and advantages will appear and be brought out more fully in the following specification, reference being had to the accompanying drawings, in which:

Fig. 1 is a perspective view of the fountain brush.

Fig. 1a is a perspective view of the rinsing device.

Fig. 2 is a plan view of the fountain brush head.

Fig. 3 is a plan view of the rinsing head.

2

Fig. 4 is an enlarged longitudinal section illustrating the connection.

Fig. 5 is a transverse sectional view on the line 5—5 of Fig. 2.

Fig. 6 is a transverse sectional view on the line 6—6 of Fig. 3.

Referring to the drawings in detail, in which I have shown the preferred form for the purpose of illustrating the principle of my invention, I have shown a brush 10, having the usual shank 11, brush head 12, and bristles 13.

Extending through the shank to the brush head is a bore 14 for a tube 15, having openings 16 in the brush head area.

15 The tube, in the form shown, is exposed in the area of the brush head, so that it can be provided with the operative water-exuding openings.

The water may be supplied from a hose connection 17 with a faucet.

20 A standard hose connection 18 has a cylindrical extension 19, having a spring 20.

Also provided on the inside of the hose extension, is a projection 21 which is adapted to cooperate with a slot 22, having an off-set 23, in the handle 11.

25 The tube 15, in the form shown, is mounted in and is rigid with the connection 18.

When it is desired to connect the source of supply to the shank, the pin 21 is brought into registry with the slot 22, and the shank is telescoped in the cylinder, compressing the spring 20; and the cylinder is rotated on the shank to turn the projection or pin into the off-set portion 23, to lock the two together.

30 The supply may be then turned on, and the device is ready for operation, as will be readily understood by those skilled in the art.

For rinsing after the brush, I have provided a rinsing device consisting of a shank 24, having 35 a massaging head 25.

The shank 24 is provided with a slot 22' similar to the slot 22, having an off-set 23' similar to the offset slot portion 23, for locking with a source of supply by means of the stud 21 in substantially the same manner as described in connection with the brush 10.

40 The shank has a bore 26, leading to the massaging head.

The massaging head has an upward extension 27, which is adapted to snugly receive an attachment 28, which may be of rubber or other pliable material which will not injure the gums, and yet permit as vigorous massaging as desired.

45 The attachment may be provided with ribs 29, if desired.

50 While I have illustrated and described the

preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

Having thus described my invention, what I claim as new and desire to secure by Letters Patent is:

1. A fountain toothbrush or similar implement comprising: a perforated head, and an elongated handle secured to said head and provided with a passage extending from the outer end of said handle, through said handle, and communicating with said perforated head; a tube of substantially rigid material, adapted to communicate with a source of liquid and to be extended into said passage, and to communicate with said perforated head; a socket member, substantially rigidly connected to said tube, contoured for the snug reception of the outer end of said handle; and means carried by said socket member and said handle for connecting said socket member and said handle, said means including a bayonet joint, and a spring encased within said socket member and adapted to bear between said socket member and the end of said handle.

2. An attachment for a toothbrush or like implement having a handle with a passage therethrough comprising: an elongated tube adapted to enter said passage, a fitting adjacent one end of said tube for connection with a source of liquid, an enlarged socket member rigidly secured on said tube spaced from the opposite end of said tube and opening toward said opposite end for the reception of said handle, and fastening means carried by said socket member detachably engageable with complementary fastening means on said handle.

3. A fountain toothbrush or like implement, comprising a hollow head and a hollow handle communicating therewith, an L-shaped bayonet slot in said handle, a tube extending into said handle, a socket rigidly secured on said tube and adapted to receive the end of said handle upon extension of said tube thereinto, and a stud in said socket adapted to securely engage in said bayonet slot upon reception of said handle in said socket and relative rotation of said handle and socket.

net slot upon reception of said handle in said socket and relative rotation of said handle and socket.

4. A fountain toothbrush or like implement comprising a hollow head and a hollow handle communicating therewith, an L-shaped bayonet slot in said handle, a tube extending into said handle, a socket rigidly secured on said tube and adapted to receive the end of said handle upon extension of said tube thereinto, a stud in said socket adapted to securely engage in said bayonet slot upon reception of said handle in said socket and relative rotation between said handle and socket, and a spring in said socket positioned to be compressed by said handle end upon insertion thereof in the socket and to exert pressure thereagainst for maintaining said stud and bayonet slot in engaged relation.

5. A fountain toothbrush or the like, comprising a passaged implement having an aperture adjacent one end and a bayonet slot having a closed end at the other end, a tubular member adapted to enter said passaged implement and having an opening adjacent its entering end registrable with said aperture, a socket rigidly secured on said tubular member adapted to receive said other end of said implement, and a stud carried by said socket for connecting engagement in said slot, the relative peripheral positioning of said opening and stud corresponding to that of said aperture and the closed end of said bayonet slot for registering said aperture and opening upon engagement of the stud at the closed end of said slot.
